(57) **CLAIM**

The ornamental design for a video projector, as shown and described.

DESCRIPTION

FIG. 1 is a front perspective view of a video projector;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines shown in the drawings illustrate portions of the video projector that form no part of the claimed design.
